(57) **CLAIM**

The ornamental design for a set of transducer-electrode pairs for a catheter, as shown and described.

DESCRIPTION

FIG. 1 is a perspective view of a set of transducer-electrode pairs for a catheter showing our new design;

FIG. 2 is a side view of the set of transducer-electrode pairs for a catheter of FIG. 1; and,

FIG. 3 is a top view of the set of transducer-electrode pairs for a catheter of FIG. 1.

The broken lines are included for the purpose of illustrating portions of the set of transducer-electrode pairs for a catheter that form no part of the claimed design.
